UNITED STATES PATENT OFFICE.

DAVID L. FORD, OF PALCO, KANSAS.

WINDMILL.

Application filed April 10, 1926. Serial No. 101,136.

The present invention relates to improvements in windmills and has for its principal object to provide a simple and efficient means for generating electric current with 5 which storage batteries may be charged or which may be otherwise employed.

One of the important objects of the present invention is to provide a windmill of the above mentioned character wherein a 10 governor is associated therewith for cutting off the operation of the windmill whenever it is desired.

A further object of the invention is to provide a windmill of the above mentioned 15 character which will at all times be positive and efficient in its operation, the same being further simple in construction, inexpensive, strong, and durable and further well adapted to the purpose for which it is 20 designed.

Other objects and advantages of the invention will become apparent during the course of the following description taken in connection with the accompanying drawings.

25 In the accompanying drawings forming a part of this application and in which like numerals designate like parts throughout the several views:

Figure 1 is a side elevation with parts 30 shown in section of the windmill constructed in accordance with the present invention.

Figure 2 is a top plan view thereof.

Figure 3 is an enlarged fragmentary side elevation of the governor showing the manner in which the same is associated with the hub of the wind wheel.

Figure 4 is the sectional view taken approximately on line 4—4 of Figure 3, looking in the direction of the arrows.

40 Figure 5 is a face view of the plate formed on the forward end of the rotatable sleeve.

Figure 6 is a sectional view taken approximately on line 6—6 of Figure 2, looking in the direction of the arrows.

45 Figure 7 is a fragmentary top plan view of the guide roller supported between the sides of the channel bar directly over the opening in the base of the channel bar, which roller forms a guide for the actuating chain, and

50 Figure 8 is a detail perspective view of the yoke member forming a part of the governor operating means.

In the drawings wherein for the purpose of illustration is shown the preferred embodiment of my invention, the numeral 1 designates the supporting means which is of a construction well known in the art, and mounted in the upper portion of the support 1 is the tubular member 2. A frame 55 designated generally by the numeral 3 is carried on the upper end of the tubular member 2 and is preferably in the form of a channel bar as is clearly illustrated in several figures of the drawings. The forward end of the channel bar is curved upwardly as clearly shown in Figure 1. The frame 3 and the tubular member 2 are adapted for rotation on the upper portion of the support 1, and to this end I provide the turn tables 4 and 5 respectively, the turn table 4 cooperating with the upper end of the support 1. The lower turn table 5 is adapted for cooperation with the bottom bearing 6 which also forms or acts as a collector ring for the negative terminal of the generator 7. The upper turn table 4 is secured to the under side of the channel bar 3, while the lower turn table 5 is carried by the lower portion of the tubular member 2. 60 65 70 75 80

A vertical bracket 8 extends upwardly from the frame 3 and is provided at its upper end with a suitable bearing 9, the same being adapted for cooperation with the bearing 10 formed on the upper curved forward end of the channel bar forming the frame 3 for supporting the horizontal shaft 11. The purpose of this shaft will be presently apparent.

A bracket 12 is provided for supporting 90 the generator 7 on the frame 3 in the manner as is more clearly illustrated in Figure 6. The generator is adapted to be operated through the medium of the intermeshing gears 13 and 14 carried on the rear end of the horizontal shaft 11 and the outer end of the generator shaft 15 respectively, in the manner as clearly illustrated in Figure 6. A suitable casing 16 is disposed over the gears for obvious purposes. 95 100

A wind wheel designated generally by the numeral 17 is secured on the outer forward end of the horizontal shaft 11, and the same comprises the hub portion 18 and extending radially from the hub portion 105 are the spoke receiving portions 19. In the

present instance, four of such spoke receiving portions are formed in the wind wheel for the purpose of supporting four spokes designated generally by the numeral 5 20 and these spokes have attached on their outer ends the vanes or blades 21. It is to be understood however that I do not wish to limit myself to the particular number of blades which may be employed in connection with the wind wheel. Each of the 10 spoke receiving portions 19 has formed therein an angular slot such as is shown at 22 with reference more particularly to Figure 4 and extending through these slots are 15 the pins 23, the forward ends of which are threaded into the respective spokes 20 adjacent the inner ends thereof. These pins extend rearwardly of the wind wheel and the purpose thereof will be hereinafter more 20 fully described.

A bearing sleeve 24 is formed on the inner end of the hub portion 18 of the wind wheel 17 and this bearing sleeve surrounds a forward portion of the horizontal shaft 11 as 25 clearly shown in Figure 1. A rotatable sleeve 25 is mounted on the forward portion of the bearing sleeve 24 and cooperating with the rotatable sleeve 25 is slidable sleeve 26 which is mounted on the rear portion of the bearing sleeve 24, a suitable key 27 being associated with the rear portion of the bearing sleeve 24 and the adjacent portion of the sleeve 26 for preventing the rotation of the sleeve 26 with respect to the bearing sleeve 24. The manner in which the rotatable sleeve and the slidable sleeve cooperate with each 30 35 other will be hereinafter more fully explained.

A face plate 28 is formed on the forward 40 end of the rotatable sleeve 25, and the same is adapted for cooperation with the spoke receiving portions 19 of the wind wheel 17 in the manner to be presently described. This face plate is provided with four angularly arranged slots 29 which are adapted 45 for cooperation with the angularly arranged slots 22 formed in the respective spoke receiving members 19, the slot 29 being disposed in opposite directions to the slots 22 as 50 is more readily obvious from the construction shown in Figure 4. For further rendering the face plate 28 light, the same is provided with the cut out portion 30. The construction of the face plate per se is clearly 55 shown in Figure 5 of the drawings. The outer free ends of the pins 23 which are carried by the inner portions of the spokes 20 project through the respective slots 29, thus providing an operative connection between 60 the rotatable sleeve 25 and the wind wheel 17.

The inner opposed end of the sleeves 25 and 26 are beveled as illustrated at 31 and 32 respectively, and the purpose of this construction will also be hereinafter more fully

described. A collar 33 is formed on the rear end of the slidable sleeve 26 and cooperating with this collar 33 is the yoke 34 which is formed on the forward end of the elongated operating rod 35, the latter being 70 disposed horizontally and having its rear free end slidable in a suitable guide way 36 provided therefor in the bracket 8. This rod 35 and the yoke 34 formed on the forward end thereof is adapted for slidable movement 75 for moving the sleeve 26 forwardly and the sliding movement of the rod 35 is accomplished by means of the operating chain 37 which is attached at its upper end to the apertured ears 38 on the rod 35 adjacent the rear end thereof. This operating chain 38 extends over a suitable guide pulley or roller 39 which is supported between the sides of the channel bar 3 directly above the opening 40 formed in the base of the channel bar and through which the chain is adapted to extend. The chain then extends downwardly through the tubular member 2, and the lower free end thereof is within easy reach of the operator. 80 85 90

An expansible coil spring 41 encircles the sleeves 25 and 26, one end of this spring being secured to the face plate 28 which is carried by the forward end of the rotatable sleeve 25, the rear or opposite end of the coil spring being threaded and extending through an apertured lug 42 provided therefor on the collar 33. A thumb nut 43 is threaded on the threaded end of the coil spring 41 and cooperates with the apertured lug 42 in the manner clearly shown in Figure 3. This construction provides a means whereby the tension of the coil spring may be adjusted. 95 100 105

Normally, the parts are arranged as shown in the drawing, and the wind wheel will be rotated by the action of the wind coming in contact with the blades 21 and the rotation of the wind wheel 17 will impart rotary movement to the shaft 11 and through the medium of the intermeshing gears 13 and 14, the generator 7 will be operated for generating current to charge storage batteries, or for any other purpose for which the electric current generated may be employed. 110 115

Whenever it is desired to cut off the operation of the wind mill, the operator pulls downwardly on the chain 37 and this will cause the rod 35 to move forwardly, and through the medium of the yoke 34 and the collar 33, the sleeve 26 will slide forwardly on the bearing sleeve 24, and the beveled forward end 32 of the sleeve 26 will cooperate with the beveled inner or rear end 31 of the sleeve 25 to effect a twisting or compression of the coil spring 41, and as a result of this action, the sleeve 25 will be caused to rotate in a clock-wise direction. 120 125

The rotation of the sleeve 25 and the face plate 28 carried on the forward end thereof 130

will cause the spokes 20 of the wind wheel to slightly rotate in their respective receiving portions 19 through the medium of the pins 23 and the cooperating slots 22 and 29 so that the blades 21 will be disposed in edge-wise relation so that the wind cannot act upon the blades of the wind wheel to effect the rotary movement of the latter. Any suitable means may be provided for holding the 10 chain 37 in its downwardly pulled position.

As soon as the chain 37 is released, the coil spring 41 will automatically return the sleeve 25 and the face plate 28 carried on the forward end thereof to their normal 15 positions, and as a result the blades 21 will again be positioned against the action of the wind to permit the wind wheel to operate in the usual manner.

It will thus be seen that I have provided 20 a governor for controlling the operation of the wind wheel and the governor will at all times be positive and efficient in its operation. The simplicity in which the present invention is constructed enables the same 25 to be easily and readily operated, and furthermore can be quickly assembled or disassembled.

While I have shown the preferred embodiment of the invention, it is to be understood that minor changes in the size, shape 30 and arrangement of parts may be resorted to without departing from the spirit of the invention and the scope of the appended claims.

35 Having thus described the invention, what I claim as new and desire to secure by Letters Patent is:—

1. In a windmill, a horizontal shaft, a 40 wind wheel comprising a hub secured on said shaft, a series of radially disposed spokes journaled for rotation in said hub, blades carried by the outer end portions of the spokes, a sleeve extension formed on the inner end of the hub and disposed over said 45 shaft, a rotatable sleeve extension, cooperative means between said rotatable sleeve and said spokes for disposing the blades in edge-wise relation, means for effecting the actuation of the rotatable sleeve, said last mentioned means comprising an additional sleeve adapted for slidable movement on the rear portion of the aforementioned sleeve extension, the inner opposed 50 end of the sleeve mounted on the sleeve extension being beveled, and a normally expanded coil spring encircling the sleeve mounted on the sleeve extension the respective ends of the spring being secured to the rotatable and slidable sleeve.

60 2. In a windmill, a horizontal shaft, a wind wheel comprising a hub secured on one end of the shaft, a bearing sleeve extending from the inner end of the hub, a series of radially disposed spokes journaled 65 for rotation in the hub, blades carried by

the outer end portions of the spokes, pins carried by the inner end portions of the respective spokes and extending rearwardly from the windwheel, a rotatable sleeve mounted on the forward portion of the bearing sleeve, a face plate carried by the forward end of the rotatable sleeve and provided with angular slots through which the outer ends of the respective pins extend, a 70 slidable sleeve mounted on the rear portion of the bearing sleeve, the inner opposed ends of the rotatable sleeve and the sliding sleeve being beveled, a collar associated with the rear end of the slidable sleeve, a normally expanded coil spring encircling said last 75 mentioned pair of sleeves, one end of the spring being secured to the face plate, the other end being secured to the collar, and means cooperating with the collar for actuating said slidable sleeve to effect the compressing of the coil spring and simultaneously 80 actuate the spokes to dispose the blades in edge-wise relation.

3. In a windmill, a horizontal shaft, a wind wheel comprising a hub secured on one end of the shaft, a bearing sleeve extending from the inner end of the hub, a series of radially disposed spokes journaled for rotation in the hub, blades carried by the outer end portions of the spokes, pins carried by the inner end portions of the respective spokes and extending rearwardly from the wind wheel, a rotatable sleeve mounted on the forward portion of the bearing sleeve, a face plate carried by the forward end of the rotatable sleeve and provided with angular slots through which the outer ends of the respective pins extend, a 90 slidable sleeve mounted on the rear portion of the bearing sleeve, the inner opposed ends of the rotatable sleeve and the sliding sleeve being beveled, a collar associated with the rear end of the slidable sleeve, a normally expanded coil spring encircling said last 95 mentioned pair of sleeves, one end of the spring being secured to the face plate, the other end being secured to the collar, and means cooperating with the collar for actuating said slidable sleeve to effect the compressing of the coil spring and simultaneously 100 actuate the spokes to dispose the blades in edge-wise relation.

4. In a windmill, a horizontal shaft, a windwheel comprising a hub secured on said shaft, a series of radially disposed spokes journaled for rotation in said hub, blades carried by the outer end portions of the spokes, a sleeve extension formed on the inner end of said hub and disposed over said shaft, a rotatable sleeve mounted on the forward portion of the aforementioned 105 sleeve extension, the inner opposed end of the sleeve mounted on the sleeve extension being beveled, and a normally expanded coil spring encircling the sleeve mounted on the sleeve extension the respective ends of the spring being secured to the rotatable and slidable sleeve.

5. In a windmill, a horizontal shaft, a wind wheel comprising a hub secured on one end of the shaft, a bearing sleeve extending from the inner end of the hub, a series of radially disposed spokes journaled 110 for rotation in the hub, blades carried by the outer end portions of the spokes, pins carried by the inner end portions of the respective spokes and extending rearwardly from the windwheel, a rotatable sleeve mounted on the forward portion of the bearing sleeve, a face plate carried by the forward end of the rotatable sleeve and provided with angular slots through which the outer ends of the respective pins extend, a 115 slidable sleeve mounted on the rear portion of the bearing sleeve, the inner opposed ends of the rotatable sleeve and the sliding sleeve being beveled, a collar associated with the rear end of the slidable sleeve, a normally expanded coil spring encircling said last 120 mentioned pair of sleeves, one end of the spring being secured to the face plate, the other end being secured to the collar, and means cooperating with the collar for actuating said slidable sleeve to effect the compressing of the coil spring and simultaneously actuate the spokes to dispose the blades in edge-wise relation.

sleeve extension, cooperative means between the rotatable sleeve and said spokes for disposing the blades in edgewise relation, said means comprising a face plate formed on the forward end of the rotatable sleeve, said hub being provided with a series of angular slots, said face plate having a series of angular slots communicating with

the aforementioned slots and disposed in opposite directions thereto, pins projecting laterally from said spokes through the respective registering slots, and means for effecting the actuation of the rotatable sleeve.

In testimony whereof I affix my signature.

DAVID L. FORD.
